PLASTIC COATED SHEET MATERIAL

Richard A. Mazur, McFarland, Wis., assignor to Uniroyal, Inc., a corporation of New Jersey

Filed Feb. 21, 1967, Ser. No. 5,893

Term of patent 14 years

(Cl. D87—3)

The figure of the drawing is a plan view of a plastic coated sheet material showing my new design.

A single repeat of the design is enclosed within the rectangle bounded by the broken lines.

I claim:

The ornamental design for a plastic coated sheet material, as shown and described.
